UNITED STATES PATENT OFFICE.

ALLISON N. CLARK, OF PLAINVILLE, CONNECTICUT.

DESIGN FOR A BODY FOR MATCH-BOXES.

SPECIFICATION forming part of Design No. 26,816, dated November 24, 1896.

Application filed September 24, 1896. Serial No. 606,894. Term of patent 14 years.

To all whom it may concern:

Be it known that I, ALLISON N. CLARK, a citizen of the United States, residing at Plainville, in the county of Hartford and State of Connecticut, have invented and produced a new and original Design for a Match-Box Body, of which the following is a specification, reference being had to the accompanying drawing, which is a perspective view of said box.

This invention relates to the class of match-boxes adapted to be secured to or hung against a wall or other vertical support, and my said invention seeks to provide a new and pleasing design for the body portion of this class of boxes.

The leading features of my design consist of a substantially square front *a*, having near its top an opening *a'*, that extends nearly

across said front. The sides *b* of said box extend rearward from the said front, and substantially at right angles thereto, a distance equal to about half the width of the front, the extreme rear edge of said sides being above and below the said front and connected with said front by angular walls *b'*, as shown in the drawings. The extreme rear edges of the sides *b* are extended toward each other, forming narrow portions *c*, that are parallel with said edges and at right angles to said sides.

What I claim is—

The design for a match-box body substantially as herein shown and described.

ALLISON N. CLARK.
